John P. Durkin

BY

ATTORNEY

UNITED STATES PATENT OFFICE.

JOHN P. DURKIN, OF PHILADELPHIA, PENNSYLVANIA, ASSIGNOR TO DURKIN CONTROLLER HANDLE COMPANY, OF PHILADELPHIA, PENNSYLVANIA, A CORPORATION OF PENNSYLVANIA.

CONTROLLER-REGULATOR.

No. 826,495.

Specification of Letters Patent.

Patented July 17, 1906.

Application filed January 8, 1906. Serial No. 294,998.

To all whom it may concern:

Be it known that I, JOHN P. DURKIN, a citizen of the United States, residing at Philadelphia, in the county of Philadelphia and State of Pennsylvania, have invented certain Improvements in Controller-Regulators, of which the following is a specification.

This invention relates to the automatic regulation of the operations of electric-motor controllers, and its leading purpose is to provide in mechanism for interrupting the action and preventing the too rapid introduction of current a simplified construction of increased durability and efficiency.

In the accompanying drawings, Figure 1 is a plan view, partially in section, representing a form of the invention. Fig. 2 is a vertical sectional view of the construction shown in Fig. 1. Fig. 3 is a vertical sectional view of a detail, taken on the line 3 3 of Fig. 1. Fig. 4 is a sectional plan view illustrating a modification in the details of construction. Fig. 5 is a vertical sectional view of a detail, taken on the line 5 5 of Fig. 4; and Fig. 6 is a vertical sectional view of a detail, taken on the line 6 6 of Fig. 4.

As shown in the drawings, the controller-shaft 1, journaled in the top 2 of the controller-casing, has sleeved thereon the dome 3 of a disk or hood 4, firmly fixed to the shaft, a set-screw 5 being passed through the dome or closed sleeve into engagement with the shaft to secure these parts together and the shaft being revolved through the hood by the handle 6. Within the hood is the circular channel 7, having zigzag sections comprising the alternating and oppositely-disposed projections or teeth 8 and 9, extending radially with reference to their path of rotation. The projections 8 have the inclined faces 8^a, being suitably V-shaped, and the projections 9, disposed between the projections 8, have the radial faces 9^a and the curved faces 9^b, being of serrated form.

In Figs. 1, 2, and 3 there is shown a way 10—an approximately U-shaped cam—formed in a member 11, which is secured to the casing-top. A ball 12 lies normally in the inner part of the cam, where its bifurcations 10^a and 10^b intersect, and in the channel 7 in the path of the projections 8, both branches of the cam having an upward inclination in the

outward direction from their intersection. Therefore when the handle 6 is revolved in the direction of the arrow the ball is carried by 55 a projection 8 along the branch 10^a into the path of the succeeding projection 9, which is engaged by the ball and the forward movement of the handle is stopped. Upon relieving the pressure on the handle, so that the ball 60 can disengage itself from the engaging projection 9, it rolls by gravity to its initial position into the path of the second projection 8, which upon the further revolution of the handle again throws the ball outwardly into 65 position to be engaged by the second projection 9. In this manner the desired interruptions are effected at the proper points in operating the controller to admit current to the motor. In revolving the handle in the opposite direction to throw off the current the ball is thrown by the projections 8 into the cam branch 10^b, where it reciprocates through the actions of the inclined faces 8^a and 9^b, from which it rolls, thus permitting an uninterrupted reverse movement. 75

In Figs. 4, 5, and 6 the part 6 is provided with a camway 13, having the elevation 13^a, from the top of which it inclines downwardly in the direction of the arrow to its part nearest the center of revolution of the channel 7, the ball 12 normally resting in the lowest point of the cam and in the channel in the path of the projections 8. In the forward revolution of the handle to admit the current the projections 8 push the ball 12 over the cam's elevation 13 into the path of the approaching projection 9, which engages the ball, and thereby checks the movement. Upon moving the handle in the reverse direction to permit 85 the ball to pass it the ball will be carried by gravity in the direction of the arrow to its initial position in the path of the second projection 8, which carries it into the path of the second projection 9. Thus there is effected 90 a positive step-by-step movement in the forward direction for the admission of current, while in the reverse movement for throwing off the current the ball plays in the camway, since it will not positively engage the inclined 95 faces 8^a and 9^b.

Having described my invention, I claim—

1. A controller-regulator comprising oppositely-disposed alternating projections, a

- cam, and a device movable by one into engagement with another of said projections under control of said cam.
2. A controller-regulator comprising a circular way having an irregular section, a movable device registering with said way for engaging irregularities of said section, and a cam for controlling the movement of said device.
3. A controller-regulator comprising a circular way having sets of oppositely-disposed projections, and a ball thrown by one set into engagement with another set of projections, said ball being automatically disengaged from said last-named projections.
4. A controller-regulator comprising oppositely-disposed alternating projections, a ball thrown by one into engagement with another of said projections and automatically disengaged from said last-named projections, and means for controlling the movements of said ball.
5. A controller-regulator comprising oppositely-disposed alternating projections extending radially with reference to the center of revolution, a ball, and a way for controlling the movement of said ball, said ball being thrown horizontally by one into engagement with another of said projections and automatically disengaged from said last-named projections.
6. A controller-regulator comprising, in combination with the controller-shaft, a device having a circular way with oppositely-disposed projections fixed to and revoluble with said shaft, a ball registering with said way and thrown by one into engagement with another of said projections, and a cam for controlling the movements of said ball.
7. A controller-regulator comprising, in combination with the controller-shaft, a hood having a circular way with oppositely-disposed projections, a reciprocating device thrown by one into engagement with another of said projections to check the revolution of said shaft, said device being automatically disengaged, and means for controlling the movement of said device and permitting said shaft to be revolved freely in the reverse direction.
8. A controller-regulator comprising, in combination with the controller-shaft, a hood provided with a circular way having a set of substantially V-shaped projections and a set of substantially radial engaging surfaces, a reciprocating device thrown by said projections into engagement with said surfaces and automatically withdrawn from the path thereof in revolving said shaft in one direction, and means whereby said shaft can be revolved freely in the opposite direction.
9. A controller-regulator comprising, in combination with the controller-shaft, a set of substantially V-shaped projections connected to and revoluble with said shaft, means providing substantially radial surfaces alternating with said projections and revoluble therewith, a ball thrown by said projections into engagement with said surfaces, and a camway for controlling the movements of said ball, said mechanism comprising means whereby the revolution of said shaft is interrupted in moving in one direction and is uninterrupted in moving in the opposite direction.
10. A controller-regulator comprising, in combination with the controller-shaft, a hood having a circular way with substantially V-shaped projections and corresponding irregularities with substantially radial and inclined surfaces, a ball normally disposed in the path of said projections and moved thereby into the path of said substantially radial surfaces to check the rotation of said shaft in one direction, and a camway for controlling the movement of said ball and enabling said inclined surfaces and projections to pass it without positive engagement in revolving said shaft in the opposite direction.
11. A controller-regulator comprising, in combination with the controller-shaft, a ball, a way by which the movements of said ball are controlled, and means coacting therewith by which said ball is moved toward and from the center of revolution to effect an interruption of the movement of said shaft.

In testimony whereof I have hereunto set my name, this 5th day of January, A. D. 1906, in the presence of the subscribing witnesses.

JOHN P. DURKIN.
